United States Patent Office

Des. 226,300
Patented Feb. 13, 1973

226,300

TEXTILE FABRIC

Leonard C. Clementi, Huntington, N.Y., assignor to Cannon Mills Company, Kannapolis, N.C.

Original design application Feb. 16, 1971, Ser. No.
115,908. Divided and this application Feb. 2, 1972,
Ser. No. 223,062

Term of patent 14 years

Int. Cl. D6—13

U.S. Cl. D6—265

Fig. 1

FIG-2

FIG. 1 is a top plan view of a textile fabric showing my new design; and

FIG. 2 is a top plan view of a second embodiment of the design shown in FIG. 1.

This is a division of design application Ser. No. 115,908, filed Feb. 16, 1971.

I claim:

The ornamental design for textile fabric, substantially as shown and described.
